CLAIM

The ornamental design for an electronic device holder, as shown and described.

DESCRIPTION

This application is related to U.S. Design application Ser. No. 29/420,451, filed May 9, 2012, the entire disclosure of which is incorporated herein by reference.

FIG. 1 is a perspective view of an electronic device holder showing our new design according to a first embodiment; FIG. 2 is another perspective view of the first embodiment; FIG. 3 is a front elevational view of the first embodiment; FIG. 4 is a right side elevational view of the first embodiment; FIG. 5 is a left side elevational view of the first embodiment; FIG. 6 is a rear elevational view of the first embodiment; FIG. 7 is a sectional view of the first embodiment taken along line 7-7 of FIG. 3;

FIG. 8 is a sectional view of the first embodiment taken along line 8-8 of FIG. 3;

FIG. 9 is a front elevational view of the electronic device holder showing our new design according to a second embodiment, the second embodiment being identical to the first embodiment except that the second embodiment includes two indeterminate lengths as indicated in FIG. 9;

FIG. 10 is a perspective view of an electronic device holder showing our new design according to a third embodiment;

FIG. 11 is another perspective view of the third embodiment;

FIG. 12 is a front elevational view of the third embodiment;

FIG. 13 is a right side elevational view of the third embodiment;

FIG. 14 is a left side elevational view of the third embodiment;

FIG. 15 is a rear elevational view of the third embodiment;

FIG. 16 is a sectional view of the third embodiment taken along line 16-16 of FIG. 12;

FIG. 17 is a sectional view of the third embodiment taken along line 17-17 of FIG. 12; and,

FIG. 18 is a front elevational view of the electronic device holder showing our new design according to a fourth embodiment, the fourth embodiment being identical to the third embodiment except that the fourth embodiment includes two indeterminate lengths as indicated in FIG. 18.

The broken lines in FIGS. 1-6, 9-15 and 18 form no part of the claimed design. The areas encircled by broken lines in FIGS. 1-3, 6, 9-12, 15 and 18 are unclaimed areas and form no part of the claimed design.
